[57] CLAIM

The ornamental design for a screwdriver, as shown and described.

DESCRIPTION

FIG. 1 is a perspective view of a first embodiment of a screwdriver showing my new design.

FIG. 2 is a bottom plan view of the first embodiment.

FIG. 3 is a top plan view of the first embodiment.

FIG. 4 is a left side elevational view of the first embodiment.

FIG. 5 is a front elevational view of the first embodiment.

FIG. 6 is a rear elevational view of the first embodiment.

FIG. 7 is a perspective view of a first embodiment in an alternate position of a screwdriver showing my new design.

FIG. 8 is a bottom plan view of the first embodiment in an alternate position.

FIG. 9 is a top plan view of the first embodiment in an alternate position.

FIG. 10 is a left side elevational view of the first embodiment in an alternate position.

FIG. 11 is a front elevational view of the first embodiment in an alternate position.

FIG. 12 is a rear elevational view of the first embodiment in an alternate position; and,

FIG. 13 is a perspective view of a second embodiment of my new design of FIGS. 1-2 wherein all other views are identical to the first embodiment except for the chuck portion.

The broken line showing of a bit holder is for illustrative purposes only and forms no part of the claimed design.
